(57) **CLAIM**

The ornamental design for a pulper blade wear shoe, as shown and described.

DESCRIPTION

FIG. 1 is a perspective view of a pulper blade wear shoe showing our new design, shown in use with a rotor blade,

FIG. 2 is another perspective view of the pulper blade wear shoe of FIG. 1, shown in use with the rotor blade of FIG. 1;

FIG. 3 is a perspective view of a pulper blade wear shoe;

FIG. 4 is another perspective view of the pulper blade wear shoe of FIG. 3;

FIG. 5 is a top view thereof;

FIG. 6 is a bottom view thereof;

FIG. 7 is a rear view thereof;

FIG. 8 is a front view thereof;

FIG. 9 is an end view thereof; and,

FIG. 10 is an opposite end view thereof.

The broken lines in the drawings depict unclaimed environmental subject matter.
